UNITED STATES PATENT OFFICE.

WALTER S. EDMANDS, OF BOSTON, MASSACHUSETTS.

ELECTRICAL CONNECTION.

1,189,435.

Specification of Letters Patent.

Patented July 4, 1916.

Application filed June 11, 1915. Serial No. 33,619.

To all whom it may concern:

Be it known that I, WALTER S. EDMANDS, a citizen of the United States, residing at Boston, county of Suffolk, State of Massachusetts, have invented a certain new and useful Improvement in Electrical Connections, of which the following is a specification, reference being had therein to the accompanying drawings.

10 My invention has for its object a new and improved coupling member for covering up and securing together connections for electric wires.

15 The device embodying my invention is particularly adapted for use where it is desired to connect electrically a series of adjacent desks, tables, individual machines or like objects so that a lamp or other electrical apparatus placed on each may be operated 20 electrically with a minimum amount of electric wiring. Since the desks, tables or machines are heavy and are sometimes moved relatively to each other, the connections must be strong so that the strain will not break 25 the connections nor injure the insulation. It is also desirable that they be so arranged that they may be quickly and easily disconnected and that all live parts be covered, when it is necessary to separate the desks 30 or machines. Also that provision be made so that additional units can be added to the line when required. Difficulty has been found heretofore in maintaining the connections intact, for the connections are frequently 35 partly separated or become wholly detached, or the metal conductor is exposed which results in cutting off the current altogether or in creating an arc which may burn the clothes of those working near by. My 40 device however is so constructed that a pair of connections may be held firmly together so that they cannot be pulled apart, the strain at the point of connection being taken by a special covering member. This member 45 also covers up that portion of the wire which is partly bared of insulation so that a firm, strong well protected connection is obtained.

50 My invention also includes a unit which may be permanently secured to each desk or other article and to which the lamp or other electrical apparatus thereon may be connected. This unit is called for convenience the desk unit. The said unit is arranged for 55 connection to the wall plug and an adjacent article of furniture or to two adjacent ar-

ticles. Another unit known as the coupling unit is also provided by which adjacent desk units are connected.

The device is preferably secured to the 60 desk or other article along the end or side preferably directly under the ledge formed by the projecting top.

The device is simple and cheap to construct and is so constructed as to prevent effectively 65 all possibility of the conductors becoming bared and producing short circuits or burning the persons or clothes of the users of the desks or the furniture itself.

In the following description, I have described 70 my invention as employed in connecting two adjacent desks, but it will be understood that I do not limit myself to this application of my invention since it may be employed in many other circumstances. 75

The invention will be fully understood from the following description when taken in connection with the accompanying drawings and the novel features thereof will be pointed out and clearly defined in the 80 claims at the close of the specification.

Referring to the drawings Figure 1 is an end view of a desk electrically connected to an adjacent desk and to a wall plug by devices embodying my invention. Fig. 2 is an 85 elevation on an enlarged scale of one of the coupling units and the adjacent parts of two desk units. Fig. 3 shows one of the coupling units detached from the other parts. Fig. 4 is a top plan view of the parts 90 shown in Fig. 2.

Referring to the drawings at A, and B are shown portions of two adjacent desks and at C a wall plug. At 11 is shown a molding or conduit within which the cable 12 lies, 95 being covered or not, as desired, by a covering strip 13 in the manner commonly employed in electrical wiring. At the ends next to the connections, the two insulated wires 14 and 15 forming part of the cable 100 12 are separated and connected electrically by the binding screws 16 (see Fig. 2) to one member 17 of a pair of plug and socket connecting members of well known form. I have shown a well known form of plug 105 and socket connecting member but I do not limit myself to this particular form since others may be employed with equal success. Adjacent this plug and socket connecting member 17 is the other plug and socket connecting member 18. In the drawings, I have 110 shown the member 17 as being provided

with a male member or plug 19 and a socket 20 while the member 18 is provided with a plug 21 and socket 22. The connecting member 18 is electrically connected with the 5 two wires 23 and 24 of a piece of cable forming part of the coupling unit. This cable extends to the wall plug, to the adjacent desk or to the piece of electrical apparatus thereon as the case may be. The cable 10 25 in the drawings extends to one connecting member 26 of another pair of connecting members located on the adjacent article of furniture. It will therefore be seen that 15 two units are formed one of which for convenience I term the desk unit and the other of which may be termed the coupling unit and that these two units are quickly and easily united or separated whenever necessary but that they are not capable of 20 resisting any considerable strain imposed upon them but will be pulled apart.

At 27 is shown a covering member consisting of a heavy strip of flat vulcanized fiber or the like preferably of an insulating 25 nature bent as shown in Fig. 4 into U-shape but with one leg longer than the other. A hole 28 permits the passage of the cable 25 and two other holes permit the passage of screws or bolts 29 and 30. The two connecting members 17 and 18 have holes 31 and 32 registering therewith to permit the passage of the said screws or bolts 29 and 30. The two wires 23 and 24 forming the cable 25 of the coupling unit are inserted through 35 an aperture 28 in the covering member 27. Then two knots 33 and 34 are tied in the wires 23 and 24 which are then secured to the connecting members by the binding screws 16. The covering member 27 lies 40 with its short leg resting against the bottom of the wire groove in the molding and with its long leg resting against the outer face of the two connecting members 17 and 18 with the holes therein in registration 45 with the corresponding holes in the connecting members. The bolts or screws 29 and 30 are then inserted thus securing the covering member 27 to the connecting members 17 and 18 and securing the whole to the 50 desk. In the drawings I have shown the use of wood screws which pass through the covering member, the connecting members, and into the wood of which the conduit 11 is made, but it will be understood that fastening means appropriate to the material 55 and structure of the conduit and article of furniture will be employed. It will be seen that any strain placed upon the cable 25 will be taken by the covering member 27 since the knots 33 and 34 are drawn against it and there will be no strain tending to pull the wires 23 and 24 out from under the binding screws 16. It will also be seen that the strain on the wire 25 does not tend to 60 pull the connecting members apart because

this strain is taken by the covering strip 27. The construction at the other end of the cable 25 is identical. When it is desired to disconnect the two articles of furniture the two screws 29 and 30 are removed after 70 which the connections may be pulled apart. I employ a similar connection to connect the desk unit with the lamp cable 36. The parts of this connection are held together by the covering member 37 and two screws 38. In 75 practice a desk unit is secured to each desk or other article of furniture or individual machine and is connected to the lamp or other piece of electrical apparatus thereon. Adjacent desks are connected by coupling 80 units and the desk at one end of the line is connected to the floor plug by the cable 39, while the desk at the other end of the line is preferably furnished with a covering member over the unconnected connecting 85 member to present a uniform appearance and make it easy to connect up the next article should another be added.

It will be understood that the desk unit may be made of any desired length, likewise 90 the coupling units, so that desks of any size may be coupled together, and so that they may be placed at any desired distance apart.

What I claim is:

1. The electric connection comprising in 95 combination, two connecting members at least one of which has a plug and the other a socket for connecting said two members, each of said two members having a cable connected therewith, and a covering tie 100 member which is rigidly secured to both of said connecting members and ties them together and has an aperture through which the cable of one of said connecting members passes, said last cable being provided with 105 a strain take-up on the inner side of said aperture which prevents the strain on the cable from being transmitted to the two connecting members, and means for detachably and rigidly securing said connecting members 110 to an article which is to be electrically connected with another article.

2. The electric connection comprising in combination, two connecting members at least one of which has a plug and the other 115 a socket for connecting said two members, each of said two members having a cable connected therewith, a covering tie member which is rigidly secured to both of said connecting members and ties them together and has an aperture through which the cable of one of said connecting members passes, said last cable being provided with a strain take-up on the inner side of said aperture which prevents the strain on the cable from being 120 transmitted to the two connecting members and means whereby said covering member may be fastened to a desk or other support.

3. The electric connection comprising in combination, a pair of male and female con- 125

necting members, a U-shaped covering member having an aperture therein and having one leg longer than the other, and a cable passing through the said aperture in the 5 covering member and knotted on the inside of the covering member, the long leg of said covering member being rigidly secured to both of said connecting members along one face, and the short leg lying in the plane of 10 the other face of said connecting member.

4. The electric connection comprising in combination, a pair of male and female connecting members, a U-shaped member having one leg rigidly connected to both of said 15 connecting members and having an aperture through its head, and a cable connected with one of said connecting members and passing through said aperture, said cable being provided with a stop on the inner side of said 20 aperture which prevents strain on the cable from being transmitted to said connecting member.

5. In combination with two articles which are to be electrically connected together, a 25 pair of members detachably secured to each of said articles, at least one of each pair of

members having a plug and the other member of each pair having a socket for connecting said two members together, a tie member for each pair which is rigidly secured to 30 both members of the pair and ties them together, each of said tie members having an aperture, a cable, one end of which passes through the aperture in the tie member on one of said articles, the other end of which 35 passes through the aperture in the tie member on the other of said articles, and a strain take-up on the inner side of each of said apertures which prevents the strain on the cable from being transmitted to either pair 40 of said connecting members, said cable being electrically connected with one member of each pair of connecting members, and separate cables electrically connected with the other member of both pairs of connecting 45 members.

In testimony whereof I affix my signature, in presence of two witnesses.

WALTER S. EDMANDS.
